UNITED STATES PATENT OFFICE.

DUDLEY JAMES BARNARD, OF BARKING, ENGLAND.

GRAB.

Application filed March 30, 1928, Serial No. 266,070, and in Great Britain March 28, 1927.

This invention relates to grabs of the type in which all movements of the grab are usually effected by a single chain or rope and in which the grab is supported by a button secured to the chain while the trip or unlocking mechanism is being disengaged from the tipping ring supported from the jib of the crane and while the grab is being lowered on to the material to be raised.

10 It has been found in practice that there is considerable difficulty in effectively securing the button to a wire rope and it is the object of this invention to provide an improved device by means of which the button is rendered unnecessary.

20 In the accompanying drawings which illustrate this invention:—Figure 1 is a side view of a grab showing the parts in the position they occupy when the grab is supported by the hauling rope. Figure 2 is a side view of the head of a grab showing the parts in the position they occupy when the grab is closed and supported by the tipping ring. Figure 3 is a front view of Figure 2 partly in section 25 on line $x-x$ of Figure 4. Figure 4 is a plan view on line $w-w$ of Figure 3. Figure 5 is a similar view to Figure 2 the bucket sections being in the open position. Figure 6 is a front elevation of the operative member, 30 and Figure 7 is a plan thereof.

In the drawings 1 and 2 are the bucket sections pivoted on independent pivot pins 3, 4 on a transverse cross beam 5 upon which are mounted the axles 6 for the lower sheaves 35 7, 8. Spreader arms 9 are arranged at each corner of the grab their upper ends being pivoted on independent pivot pins 10, 11 secured in brackets carried by the block plates 12 which constitute the head of the grab, said 40 plates being suitably spaced apart and carrying between them the axle 13 of the sheaves 14. Centrally disposed between the two inner block plates 12 is a thimble 15 preferably formed in two parts. The exterior of 45 the thimble 15 is preferably of rectangular form so as to enable it to fit and be firmly secured to and between the inner block plates 12 and the interior of cylindrical form so as to permit the sliding or operative member 16 to reciprocate therein.

50 The trip mechanism comprises a pair of hook-shaped elements 17 provided with pins 18 slidably mounted in slots 19 provided in lugs 20 on the thimble 15 and the lower ends 55 of said elements are provided with inwardly disposed projections 21 adapted to pass

through slots 2 provided in the thimble 15 and through corresponding slots 22* provided in the operative member 16.

The lower end of the member 16 is provided with a cross bar 23 adapted to coact with and be gripped at each end of the bar by four lugs or projections 24, constituting two pairs of gripper hooks. The upper ends of each pair of spreader arms 9 and the opposed hinged portions of the bucket sections 1 and 2 are preferably provided with interengaging toothed members 25, 26 to assist in maintaining the balance of the grab when opening and to prevent any irregular movement of the spreader arms.

60 The upper ends of the hook-shaped elements 17 are adapted to coact with the upturned lower edge of a tipping ring 27 supported by the jib of the crane in the well-known manner.

65 In operation, when the grab is closed and is being lifted by the hauling rope 28, the cross-bar 23 is located below and out of engagement with the under faces of the gripper hooks 24 as shown in Figure 1. When the hook-shaped elements 17 are in engagement with the tipping ring the operative member 16 is lifted by the projections 21 and the cross-bar 23 is drawn up against the under 70 faces of the gripper hooks 24 as shown in Figure 2. If now the rope 28 is paid out the bucket sections 1 and 2 begin to open and the gripper hooks 24 slide over the upper face of the cross-bar 23 thereby reducing the space 75 between their gripping faces. As the distance between the pivots 30 of the lower ends of the spreader arms 9 decreases, which takes place as the bucket sections pass into the fully open position, the space between the gripping faces of the gripper hooks increases and the cross-bar 23 is drawn in between same, and in order to avoid the sudden jarring effect the inward movement is resisted by a pair of spring pressed pins 29 slidably 80 mounted in lugs or brackets provided on the block plates 12. When the hauling rope is drawn in the buckets close slightly and cause the gripper hooks 24 to grip the cross-bar 23. With the parts in this position the grab may 85 be drawn upwardly to release the hook shaped elements 17 from the tipping ring 27 and lowered on to the material to be raised.

90 When in this position the hauling rope is paid out, the weight of the grab being removed from the spreader arms, the cross-bar 95 drops free from between the gripper hooks 100

this dropping movement being assisted by the spring controlled pins 29. The grab may now be closed and raised.

What I claim is:—

- 5 1. In a grab of the kind herein described having a cross-beam, a sheave block carried thereby, means mounted on the head of the grab comprising a pair of block plates, a centrally disposed thimble mounted between said plates, a member slidably arranged within said thimble, a cross-bar on said slidable member and through which the hauling rope is adapted to pass to the sheave block, a pair of oppositely disposed hook-shaped elements 10 pivotally mounted on the block plates the lower ends of said hook-shaped elements being arranged to project through apertures provided in the thimble and sliding member, and means on the spreader arms adapted 15 to coact with the cross-bar on the sliding member.
- 20 2. In a grab of the kind herein described having a cross-beam, a sheave block carried thereby, a combination of devices on the head of the grab comprising a pair of block plates, a centrally disposed thimble mounted between said plates, a member slidably arranged within said thimble and through which the hauling rope is adapted to pass to the sheave block, slots provided in said thimble, a pair of oppositely disposed hook-shaped elements 25 pivotally mounted in said slots, vertically disposed slots provided in the thimble and sliding member through which the lower ends of said hook-shaped elements are arranged to project, lugs provided on said block plates, a pair of spring 30 pressed pins slidably mounted in said lugs the lower ends of said pins being arranged to 35 press against the cross-bar, and gripper hooks formed on the spreader arms adapted to coact with the cross-bar on the sliding member.
- 40 3. In a grab of the kind herein described 45 having a cross-beam, a sheave block carried

thereby, a combination of devices on the head of the grab comprising a pair of block plates, a centrally disposed two part thimble mounted between said plates, a tubular member 50 slidably arranged within said thimble, a cross-bar on the lower end of said tubular member and through which the hauling rope is adapted to pass to the sheave block on the cross-beam, slots provided in said thimble, a pair of oppositely disposed hook-shaped 55 elements pivotally mounted in said slots, means on the lower ends of said hook-shaped elements adapted to coact with the tubular sliding member, means located between the block plates adapted to coact with the cross-bar tending to maintain the latter in its lowermost position, and means on the spreader arms adapted to coact with said cross-bar.

4. In a grab of the single rope type comprising a cross-beam, a sheave block and a pair of bucket sections carried thereby, a combination of devices forming the head of the grab spreader arms connecting the bucket sections with the head of the grab, said head comprising a pair of block plates, sheaves carried thereby, a centrally disposed two part thimble mounted between said plates, a tubular member arranged within said thimble, a cross-bar on the lower end of said tubular member and through which the hauling rope is adapted to pass to the sheave block on the cross-beam, oppositely disposed lugs formed on said thimble, slots formed in said lugs, a pair of hook-shaped elements pivotally 70 mounted in said slots, vertically disposed slots provided in the thimble and sliding member, means on the hook-shaped elements adapted to enter the slots in the thimble and sliding member, spring controlled means 75 located between the block plates adapted to coact with the cross-bar and gripper jaws formed by and between the ends of the spreader arms adapted to coact with the cross-bar on the sliding member.

DUDLEY JAMES BARNARD.
